INVENTOR:

Archibald Smith

UNITED STATES PATENT OFFICE.

AURELIUS SMITH, OF INDIANAPOLIS, INDIANA.

READJUSTABLE CUSHION SHOE HEEL.

Application filed October 27, 1924. Serial No. 746,195.

To all whom it may concern:

Be it known that I, AURELIUS SMITH, a citizen of the United States, residing at Indianapolis, in the county of Marion and 5 State of Indiana, have invented a new and useful Readjustable Cushion Shoe Heel, of which the following is a specification, reference being had to the accompanying drawings, and to the letters and figures of reference marked thereon.

My invention relates to the type of shoe heel that is mainly composed of non-metallic substance, such as composition similar to that commonly used for so-called rubber 15 shoe heels, the invention having reference more particularly to a cushion heel having a wearing part that may be readjusted repeatedly as edge portions wear away, and which may be of the low heel type desired 20 by many users.

An object of the invention is to provide an improved readjustable cushion heel that shall be of such construction as to permit of a high degree of comfort and convenience 25 of the user, and especially when a low and broad heel is desired.

Another object is to provide a readjustable cushion heel which shall have great efficiency and durability.

30 A further object is to provide improved yielding parts adapted to co-operate to maintain firm footing of the user, even when edge portions of a main cushion part or heel tap have become worn away.

35 A still further object is to provide improved heel parts that shall be of simple and inexpensive construction, not costly, and which may be readily applied, readjusted, or replaced at small cost when finally 40 worn away.

With the above-mentioned and other objects in view, the invention consists in improved heel taps adapted to be readjusted rotatively and also to be inverted, in a 45 novel shim to constitute a backing for a worn cushion heel tap, in a novel front or corner part to afford a firm tread, and in an improved guard or casing; the invention consisting also further in the parts and combinations and arrangements of parts as 50 hereinafter particularly described and subsequently claimed.

Referring to the drawings,—Figure 1 is a fragmentary side view of a shoe or boot 55 having the improved heel applied thereto;

Fig. 2 is a perspective view of the guard or casing part of the heel; Fig. 3 is a bottom plan of the heel as preferably constructed; Fig. 4 is a perspective view of the front corner part of the heel; Fig. 5 is a longitudinal vertical central section of the improved heel; Fig. 6 is a view similar to the preceding figure excepting that a tap partially worn at the edge is inverted to present an unworn face; and Fig. 7 is a perspective view of the novel backing shim comprised in the invention.

Similar reference characters in the different figures of the drawings indicate corresponding elements or features of construction herein referred to in detail.

In the drawings the numeral 1 indicates the rearward portion of the main or upper part of a shoe or boot and 2 the rearward or heel portion of the sole thereof. The improved heel includes a guard or casing which may be composed of thin sheet metal and comprise a curved portion 3 and two side portions 4 and 5 having holes 6 to receive securing nails 7 to be driven into the edge of the sole to which the guard is fitted, the curved portion 3 preferably being tapered; and the guard includes also front portions 8 and 9 suitably cut away so that the tops may fit against the under side of the shoe sole, such front parts being either straight or curved according to preference, and are provided with ears 10 and 10' respectively whereby to secure them to the shoe sole. Preferably the outer side 90 of the shoe sole has a thickening piece 11 secured thereto by means of nails 12, the piece being placed so as to be approximately central in the guard or casing.

Yielding pads or lifts 13, 13', constitute 95 the main portion of the heel and they have convex edges, each pad preferably being cylindrical, the faces preferably being slightly concave. Each pad preferably has a layer of fabric reinforcement 14 therein, and each face has a central recess 15 therein to receive the piece 11 when placed adjacent to the shoe sole. Each pad has also a plurality of holes 16 therein arranged adjacent to the edge thereof, being arranged in a circle when the pad is cylindrical, to receive securing screws or spurs, the holes having countersunk ends.

An annular shim 17 is provided which corresponds to the pad in shape and size 110

excepting that it may have less thickness, and one face thereof is concave, the shim being composed of suitable non-metallic material, preferably being resilient or yielding.

6 A disk 18 is provided that has a convex face which is arranged against the concave face of the shim, a portion of the disk protruding into the opening in the shim, the disk being detachably secured by suitable means

10 to the shim. Preferably a layer of fabric 19 is secured to the protruding portion of the disk and to adjacent portions of the shim. The disk may be composed of inexpensive material, such as molded plastic

15 paper stock to be discarded without material loss when not further needed. The fabric 19 may be pressed into the surface of the parts and cemented thereto, to secure the parts together, and assist in maintaining

20 the shape of the shim. The shim and its filling disk is to be carried in the heel behind the pad or one of the plurality of pads, until needed to serve as a backing for the pad when the pad is inverted after its original

25 front face has become rounded from long use and wearing away at its edge. The disk has a central hole 20 and the shim has a hole 21 to receive screws 22 and 23 respectively that are inserted through the pad or heel lifts into the shoe sole. The heel proper is preferably located forward of the curved portion 3 of the guard, which may in some cases be desired, and a shim 24 is set into the space left between the pad and the adjacent portion of the guard or casing, the shim having tapered end portions to effect neat fitting in the available space. The base portion of the shim that is adjacent to the shoe sole is relatively thicker than the opposite edge portion of the shim, corresponding to the inclination of the rear portion 3 of the guard.

The heel pad is adjustable to permit a worn rear portion to be turned to forward position, whether the cushion pad is cylindrical or oval in plane, as is understood, and in order that the heel shall have amply broad support for the user, the heel is provided with forward corner portions 25 and 26 which may conveniently be integral with a tie member 27 so as to be composed of a single piece or heel member. The corner portions have recesses 28 and 28' respectively in each opposite face thereof and counter-sunk holes 29 and 29' respectively to receive screws 30 and 30' respectively whereby to detachably secure the forward heel member to the shoe sole, the normally rear portion of the member having a concave side 31 abutting the curved edge of the cushion pad or pads comprised in the heel. The forward side 32 of the front member preferably has a guard plate 33 arranged thereon which has ears 34 and 34' on its back edge whereby to secure the plate to the shoe sole, and

the plate has apertures 35 and 35' therein receiving screws 36 and 36', respectively that are screwed into the corner portions 25 and 26 respectively, permitting the corner portions to be inverted when its front edge portions 70 become worn away. The corner portions may be made of such material as may be desired, depending upon the needs of the user, being of special advantage to the user who may frequently use stairways, protecting the forward portion of the heel against excess wear.

In some cases, for economical or other reasons, the guard or casing portions 8 and 9, or the entire guard and the shim 24 may be omitted, particularly when a low heel comprising a single pad is desired.

In practical use the rearward portion of the bottom of the heel becomes worn away while the forward portions remain in good 85 condition a considerable length of time, so that the usefulness of the heel is not impaired when the worn portion of the pad is turned around to the front corner portions, but the life of the heel is extended 90 because of the new portions being brought to the rear. When the front face of the cushion pad has become convex due to wearing away at the edge, the filling disk is detached from the annular shim, and the 95 concave side of the shim is placed against the convex face of the pad, the shim being placed against another pad or heel lift, or obviously may be placed against the shoe sole when only one cushion pad or heel tap 100 is desired, and the several parts are secured to the shoe sole as indicated. In some cases portions of the shim 17 may be cut away if not needed as a backing, the remaining portions of the shim being held in place by 105 the fabric 19. The corner portions of the heel may have become considerably worn before they need to be inverted or replaced by new ones.

What is claimed as new is:

1. A cushion shoe heel including a yielding pad with a convex edge, the pad having a central screw-receiving hole, a corner-forming heel member having a concave side abutting the edge of the pad, and a plate 115 secured to the heel member opposite to the concave side thereof and having an ear thereon to secure it in place.

2. A cushion shoe heel including a yielding pad, and an annular shim having a concave side and a disk having a convex side 120 removably arranged on the concave side of the shim, the disk having a central portion projecting into the opening in the shim, and a fabric layer detachably secured to the central portion of the disk and the adjacent portions of the shim, the shim being adapted 125 to be arranged behind the pad.

3. A cushion shoe heel including a casing having a front portion and a curved rear 130

portion, a yielding pad arranged in the casing and having a convex edge, the pad having corner-forming portions extending to the front portion of the casing, each corner-forming portion having a concave side abutting the convex edge of the pad, and a shim arranged between the convex edge of the pad and the curved portion of the casing, said shim acting to hold said yielding pad so that its rear edge will be ahead of the rear edge of said casing.

4. A cushion shoe heel including a yielding pad, and an annular shim having a concave side and a disk having a convex side 15 movably arranged on the concave side of the shim, the disk having a central portion projecting into the opening in the shim, the shim being adapted to be arranged behind the pad.

5. A cushion shoe heel including an invertible ground-engaging pad and a removable annular shim arranged above said

pad, said shim being approximately wedge-shaped in cross-section.

6. A cushion shoe heel including an invertible ground-engaging pad and a removable shim arranged above said pad, said shim being composed of two separable superposed parts which form when together a stable seat for the unworn side of said pad, and one of said shim parts being shaped to fit the worn side of said pad after said pad has been inverted.

7. A cushion shoe heel including a casing adapted to be attached to the vertical sides 35 of the rear part of a shoe sole, a yielding pad arranged within said casing and extending below it, and a shim in rear of said pad and lying between said pad and said casing to carry the rear edge of said pad 40 ahead of the rear edge of said casing.

In testimony whereof, I affix my signature on the 25th day of October 1924.

AURELIUS SMITH.
